UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

TAIL SHELF FOR STEREOTYPE PLATE CASTING MACHINES

Application filed April 6, 1929. Serial No. 353,202.

This invention relates to a support for receiving the tail when it is cut off a plate on the cylinder of a casting machine.

The principal objects of the invention are 5 to provide a shelf in suitable position so that it will support the tail when it is cut away and the operator will have the option to remove the tail or the plate first, as may be convenient; to arrange it in such a position that 10 there will be sufficient room for removing the plate underneath it, and to provide a suitable support for the shelf.

Reference is to be had to the accompanying drawings in which

15 Fig. 1 is a plan of an autoplate casting machine showing a preferred form of this invention applied thereto;

Fig. 2 is a side view of the same with the plate shown in section;

20 Fig. 3 is a front view, and

Fig. 4 is a plan, similar to Fig. 1, but taken below the shelf with the mold closed and with the plate stripped from the core.

This invention is shown as applied to an 25 autoplate machine in which the casting is produced vertically. Only enough of the machine is illustrated to show the relation of this device to it.

The frame 10 of the machine is, as usual, 30 provided with a track carrying rollers 11 which support a pivoted back 12. The casting core or cylinder 13 is mounted on a stationary axis to rotate from casting position to delivering position and it delivers the plate on the 35 side opposite the back which reciprocates in a vertical position.

The saw 14 for cutting off the tail is shown 40 in its usual position in this class of machines and capable of moving from the full line to the dotted line position, as shown in Fig. 1, to trim off the tail as the cylinder rotates with the casting thereon. The cutting of the tail by this saw leaves the printing plate P and the tail T in the condition indicated in 45 full lines in Fig. 2.

Secured to the frame at the end is a bracket 50 15 extending upwardly and the receiving shelf 16 is secured at one end to the top of this bracket. The other end is supported by a vertical rod 17, which is firmly secured to

the bed plate 18. The shelf is supported at such a height that there will be enough space between the shelf and the front plate 19 so that the plate can be removed between them. The shelf is cut away at the point 20 55 to clear the path of the cutting saw.

The plate is cast and the casting delivered and the tail cut off in the usual way, leaving the tail on the cylinder 13 as indicated in full lines in Fig. 2. The shelf 16 projects 60 just to the outer surface of the plate or tail and is beveled off on the inner edge so that the tail can be simply loosened from the cylinder and pulled forwardly on the shelf 65 which will support it. This leaves the plate P underneath the shelf but this can be removed in a similar way.

In dotted lines in Fig. 2, both the plate and the tail are shown as being drawn back from the cylinder. The shelf is supported 70 in horizontal position and firmly secured in place by the supporting devices described. This method of supporting the tail obviates the need of providing means on the cylinder itself for holding the tail on it. It allows an operator to remove either the plate or the tail first, as may be convenient for him. The device is simple and inexpensive and an important convenience to the operator. 75

Although I have illustrated and described 80 only one form of the invention I am aware of the fact that modifications can be made therein by any person skilled in the art without departing from the scope of the invention as expressed in the claims. Therefore, 85 I do not wish to be limited in this respect but what I do claim is:—

1. The combination with a stereotype plate casting machine having means for delivering the united tail and plate on the 90 side away from the casting back and in vertical position and a saw for cutting the tail from the plate as the plate is delivered, of a shelf located in a position to surround the outer side of the cylinder for receiving the tail when it is detached from the cylinder. 95

2. The combination with a stereotype plate casting machine of the vertical type and a saw located in horizontal position for sev- 100

ering the tail from the plate as the cylinder of the mold rotates through a half revolution, of a horizontal shelf located at the level of said saw and of a substantially semi-cylindrical form and extending around the core in position to receive the tail when drawn out horizontally from the cylinder.

3. The combination with a vertical stereotype plate casting machine, of a shelf arranged horizontally to support the tail when drawn forwardly from the cylinder and spaced from the front plate of the casting machine sufficiently to allow the trimmed stereotype plate to be moved out between them.

4. The combination with a vertical stereotype plate casting machine, of a bracket secured to the frame and extending upwardly therefrom, a rod secured to the bed plate and extending upwardly therefrom, a horizontal plate mounted on said bracket and rod at its opposite ends and a rotatable cylinder arranged with its axis between the bracket and rod.

5. The combination with a stereotype plate casting machine having means for delivering the united tail and plate on the side away from the casting back and in vertical position, and a saw for cutting the tail from the plate as the plate is delivered, of a shelf located in a position to surround the outer side of the cylinder for receiving the tail when it is detached from the cylinder, said shelf being relatively thin and supported at its ends only and having a bevelled edge adjacent the casting whereby said tail and plate may be drawn past the bevelled edge with the tail resting on the shelf and the plate underneath the shelf.

6. The combination with a stereotype plate casting machine of the vertical type and a saw located in horizontal position for severing the tail from the plate as the cylinder of the mold rotates through a half revolution, of a horizontal shelf located at the level of said saw and of a substantially semi-cylindrical form and extending around the core in position to receive the tail when drawn out horizontally from the cylinder, said shelf having a bevelled forward edge to facilitate reception of the tail, said shelf being supported at its end only and of such thinness as to permit passage of the plate to a position beneath the shelf.

7. The combination with a vertical stereotype plate casting machine of a shelf arranged horizontally to support the tail when drawn forwardly from the cylinder and spaced from the front plate of the casting machine sufficiently to allow the trimmed stereotype plate to be moved out between them, said shelf having a bevelled forward edge to facilitate passage of the tail onto the shelf.

8. The combination with a vertical stereo-

type plate casting machine, of a bracket secured to the frame and extending upwardly therefrom, a rod secured to the bed plate and extending upwardly therefrom, a horizontal plate having a bevelled forward edge mounted on said bracket and rod, at its opposite ends and a rotatable cylinder arranged with its axis between the bracket and the rod.

In testimony whereof I have hereunto affixed my signature.

HENRY A. WISE WOOD.
